BOX WITH INWARDLY TELESCOPING COVER

Joseph Glenn Rabby, Jacksonville, Fla., assignor to National Container Corporation, New York, N. Y., a corporation of Delaware

Application October 15, 1952, Serial No. 314,829

8 Claims. (Cl. 229—43)

The present invention relates to a box and cover construction adapted to provide the greatest security to the contents of the container despite rough and careless handling.

A serious problem encountered in the shipping of goods in containers having separate top closures which are telescoped with respect to the container derives from the fact that those who handle the loaded containers are usually hasty and careless. When the containers are to be lifted the handlers will grasp any accessible portion of the container. When telescoping covers are employed, such covers in the past telescoping over the outside of the container, the exposed rim of the cover becomes quite accessible and is often, and indeed usually, grasped by handlers when the container is to be lifted. Provision is generally made for locking the cover on the container but these locking arrangements are not designed to withstand the stresses and strains incident to the lifting of the container and its contents solely by the container cover, as often occurs. Hence the covers are frequently wrenched completely off the containers before the containers ever reach their destination. Damage to and loss of the contents is an almost inevitable consequence.

The present invention avoids this difficulty by so constructing the container and the cover that the depending portions of the cover adapted to telescope with respect to the container slide inside the container side walls, the top wall of the cover snugly fitting over and sealing the open top of the container. The sides of the container are therefore smooth and free of obstructions and the cover cannot be grasped by handlers, who must therefore lift or move the container in a conventional manner more compatible with the security of the container and its contents.

In order to ensure proper orientation of the top cover, to prevent the top cover from being pushed too far into the container, and to secure the cover in place, the side walls of the container are provided with flaps of abbreviated height foldably secured to the upper edges thereof and slots of appreciable length are provided at the fold-lines therebetween, the leaves depending from the top wall of the cover telescoping with respect to the container side walls by passing through those slots between the side walls and the flaps, the cover top wall thus resting on top of the container and its inward motion being limited by its engagement with the flaps. In addition, the telescoping leaves have a height greater than the height of the flaps connected to the container side walls, so that portions of the leaves extend below the lower edges of the flaps. These extending leaf portions carry securing structure, here specifically disclosed as foldable tabs, which, after the leaves have been slid between the container side walls and flaps, are bent out beneath the lower edges of the flaps. Finger holes may be provided in the container side walls, those finger holes registering with the tabs and providing access thereto so that proper securing action of the tabs is ensured. The securing structure is sufficiently strong so that if the box should be lifted while in

2

inverted condition the weight of the contents of the container will be supported.

So positive and permanent is the operation of the securing structure that when the loaded container has reached its destination the cover can be removed only by cutting the container open. The fact that the container and cover are thus destroyed after one use is not a significant factor, since the containers are inexpensive and are normally so damaged in transit that they would not be reusable in any event.

To the accomplishment of the above, and to such other objects as may hereinafter appear, the present invention relates to the construction of a container and a cover therefor as defined in the appended claims and as described in this specification, taken together with the accompanying drawings in which:

Fig. 1 is a top plan view of a blank from which the container body may be formed;

Fig. 2 is a top plan view of the blank from which the top cover may be formed;

Fig. 3 is a three-quarter perspective view, taken partially from above, showing the container body in partially erected condition;

Fig. 4 is a view similar to Fig. 3 but showing the container body in almost completely erected condition, the bottom flaps having been folded under the open bottom of the tubular container and some of the top flaps having been folded down into operative position;

Fig. 5 is a three-quarter perspective view, taken partially from above, showing the container cover partially erected;

Fig. 6 is a view similar to Fig. 4 but showing the container fully erected and the cover in place;

Fig. 7 is a cross sectional view taken along the line 35 7—7 of Fig. 6; and

Fig. 8 is a cross sectional view of the container, showing one of the cover leaves in telescoped position and with the securing structure rendered operative.

The container and cover as here specifically disclosed are designed in the form of a half-bushel hexagonal tube for the shipment of fruits and vegetables and particularly adapted for express shipments of fancy fruits. It may, however, take numerous other forms and shapes without departing from the present invention.

The container body A is formed from the blank of Fig. 1, that blank including a plurality of panels 2 and 2' connected by fold lines 4 and defining the side walls of the container. Alternate ones of these panels, here shown as the panels 2, are provided with lateral slots 6 near the lower edges thereof. The end panel 2' is provided with a securing flap 8 connected to its side edge by means of fold line 10. Alternate ones of these panels, here shown as the panels 2' have flaps 12 foldably connected to the lower edges thereof by means of fold lines 14, these flaps having a length such as to extend, when the container is erected, across the bottom of the container from the side wall panel 2' to which it is foldably connected to the opposite side wall panel 2. Connecting portions 16 are foldably connected to the free ends of the flaps 12 by means of fold lines 18, those connecting portions terminating in flaps 20 of a size such as to fit through the slots 6 in the panels 2, the flaps 20 having tabs 22 foldably connected to the end edges thereof.

Each of the side wall panels 2 and 2' has a flap 24 connected to the upper edge thereof by means of fold line 26, a slot 28 of appreciable length, less than but preferably constituting a major proportion of the width of the side wall panels 2 and 2' respectively, being formed in the fold line 26.

The container body is erected by folding the side wall panels 2 and 2' along the fold lines 4 until the outer edge of the left hand panel 2 abuts the fold line 10, the securing

flap 8 being folded inside the left hand panel 2 and secured thereto by means of staples or the like 29 in a conventional manner. (See Fig. 3.) Thereafter the flaps 12 are folded across the open bottom of the tube defined by the side wall panels 2 and 2', the width of a given one of the flaps 12 being insufficient to close that bottom but the flaps 12 when folded overlapping so as to fully close the bottom. The connecting portions 16 are bent up along the outside of the side wall panels 2, the tabs 22 are folded so as to lie on top of the flaps 26, the flaps 20, with the tabs 22 thus positioned, are passed through the slots 6 in the side wall panels 2, and the tabs 22 are then folded out so as to positively prevent withdrawal of the flaps 20 from the slots 6, thus firmly securing the bottom flaps 12 in place and holding them with sufficient strength so as to withstand the weight of the contents of the container. It may be pointed out that these bottom-closing steps are not performed at the factory, the container body being shipped in collapsed condition, bent along opposite fold lines 4, with the flaps 12 in line with the side wall panels 2', the final erection steps being carried out at the point of use and when the container is to be filled.

The only erection step remaining, insofar as the container body A is concerned, is to fold the flaps 24 inwardly about the fold lines 26 so that they extend along the inner surfaces of the side wall panels 2 and 2' to which they are connected, the slots 28 thus being exposed at the top of the container (see Fig. 4).

The container cover B is formed from the blank of Fig. 2, and includes a top wall 30 of the same size and shape as the horizontal cross section of the container body A. Leaves 32 are foldably secured to the edges of the top wall 30 by fold lines 33, the width of the leaves 32 being substantially the same as the length of the slots 28 in the container so as to be passable through those slots and between the container side wall panels 2 and 2' and their associated flaps 24. The height of the leaves 32 is greater than the height of the container flaps 24, so that portions 34 of the leaves 32 will extend below the lower edges of the flaps 24. These extending leaf portions 34 are provided with securing structure adapted, when the leaves are telescoped, to cooperate with the lower edges of the container flaps 24 so as to positively hold the cover B in place. As here disclosed, the securing structure is defined by a pair of tabs 36 formed in the extending leaf portions 34, extending to the lower edges thereof, being inwardly spaced from the side edges thereof, normally being in the plane of the leaves 32, but being bendable out therefrom about the fold lines 38. The container side wall panels 2 and 2' are provided with finger holes 40 adapted to register with the tabs 36 when the leaves 32 are fully telescoped.

The container flaps 24 are normally folded down inside the container side wall panels 2 and 2' before the container has been completely filled, subsequent filling of the container causing the contents thereof to engage the flaps 24 and hold them in position. After the container has been filled the leaves 32 of the cover B are folded down (see Fig. 5) those leaves then being passed through the slots 28 and telescoped inside the container side walls 2 and 2' until the cover top wall 30 rests on top of the container. As may best be seen from Fig. 7, the outer edges of the cover B are inwardly spaced with respect to the outer surfaces of the container side walls 2 and 2'. Engagement between the cover top wall 30 and the container flaps 24 adjacent the fold lines 26 positively limits the degree to which the cover B may be pushed down into the container A. Thereafter, the tabs 36 may be pushed out from the plane of the portions 34 of the leaves 32 which extend below the lower edges of the flaps 24 by pressing inwardly with the finger or with a tool through the holes 40 in the container side wall 2 or 2'. As may best be seen from Fig. 7, these tabs 36 extend under the lower edges of the flaps 24 and are closely adjacent thereto. Hence removal of the cover B is

positively prevented. Moreover, if the container should be inverted so that the weight of the contents thereof will be exerted downwardly on the cover top wall 30, separation of the cover B from the container A will be prevented by interengagement between tabs 36 and the lower edges of the flaps 24. Since this interengagement will be in the direction of the height of both of those structural elements, the securing action will be quite strong, much stronger than if stress had been exerted in the direction of the thickness of one of those elements. Moreover, since two securing tabs 36 are provided for each leaf 32, those tabs 36 being symmetrically spaced with respect to the width of the leaves 32, a balanced and double-strength securing action will take place.

It will be apparent that with the construction above described no portion of the cover B is exposed for grasping. Therefore it is impossible for a handler to attempt to lift the loaded container either wholly or partially by its cover B. Moreover, the finger holes 40 provide a hand-hold which invites use by handlers of the loaded containers. If the finger holes 40 are thus used, the weight of the container will be supported almost exclusively by the upper edges of the finger holes 40 and the lower edges of the flaps 24, the container body A itself thus taking the strain. In addition, since the finger holes 40 are positioned closer to the upper edge of the container body A than to its lower edge, handlers of the loaded container are thus invited to lift and carry the containers in an upright rather than in an inverted condition, thus making it more likely that the weight of the contents of the containers will almost always be borne by the bottom flaps 12 specifically designed for that purpose.

While but a single embodiment of the present invention has been here disclosed it will be apparent that many variations may be made therein as to size, shape and other details without departing from the spirit of the invention as defined in the following claims.

I claim:

1. In combination, a container comprising side walls, flaps of abbreviated height foldably secured to the upper edges of said side walls and folded down inside said side walls, said container having slots of appreciable length, less than the width of said side walls, adjacent the fold line between said side walls and said flaps, and said side walls having finger holes under said slots and positioned below said slots by a distance slightly greater than the height of the flaps foldably secured to said side walls, and a cover comprising a top wall with leaves depending therefrom, said leaves having a width corresponding to the length of said slots and being passable through said slots between said side walls and said flaps, said leaves having a height greater than the height of said flaps so that a portion of said leaves extends below the lower edges of the flaps associated therewith when said top wall rests on the top of said container, said extending leaf portions having tabs bendable out therefrom so as to project under said flap edges and registrable with said finger holes.

2. The combination of claim 1, in which said side walls are provided with a pair of finger holes positioned inwardly with respect to the ends of the slots associated therewith, and in which said extending leaf portions have a pair of bendable tabs registrable respectively with said fingerholes, the entire bodies of said tabs being spaced inwardly from the side edges of said leaves.

3. A container-cover combination, said container comprising side walls having flaps of abbreviated height foldably secured to the upper edges thereof, extending down alongside said side walls and having slots of appreciable length, less than the width of said side walls, adjacent the fold lines between said side walls and said flaps, said cover comprising a top wall of substantially the same shape and size as the inside cross section of said container, and leaves depending from edges of said top wall, said leaves having a width corresponding to the length

of said slots and passable through said slots between said side walls and said flaps, said leaves having a height greater than the height of said flaps so that portions of said leaves extend below the lower edges of the flaps associated therewith when said top wall rests on the top of said container, and securing structure on said extending leaf portions and engageable beneath said lower flap edges so as to prevent removal of said cover, said cover being entirely within the confines of a vertical projection of said container.

4. In the combination of claim 3, said side walls having finger holes opposite said securing structure when said cover top wall rests on the top of said container, thereby providing access to said securing structure, said securing structure being normally located in the plane of said leaves but bendable out therefrom into edge-engaging position.

5. In combination, a container comprising side walls, flaps foldably secured to the upper edges of said side walls and folded down inside said side walls, said container having slots of appreciable length, less than the width of said side walls, adjacent the foldlines between said side walls and said flaps, said flaps having downwardly facing exposed edges spaced downwardly from said side wall upper edges and under said slots, said side walls having fingerholes under said slots and in registration with and immediately below said downwardly facing flap edges, and a cover comprising a top wall with leaves depending therefrom, said leaves having a width corresponding to the length of said slots and being passable through said slots between said side walls and said flaps, said leaves having a height such that a portion of said leaves extends below said downwardly facing flap edges when said top wall rests on the top of said container, said extending leaf portions having tabs bendable out therefrom so as to project under said downwardly facing flap edges and registrable with said fingerholes.

6. The combination of claim 5, in which said side walls are provided with a pair of finger holes positioned inwardly with respect to the ends of the slots associated therewith, and in which said extending leaf portions have a pair of bendable tabs registrable respectively with said finger holes, the entire bodies of said tabs being spaced inwardly from the side edges of said leaves.

7. A container-cover combination, said container comprising side walls having flaps foldably secured to the upper edges thereof, extending down alongside said side walls and having slots of appreciable length, less than the width of said side walls, adjacent the foldlines between said side walls and said flaps, said flaps having downwardly facing exposed edges spaced downwardly from said side wall upper edges and under said slots, said cover comprising a top wall of substantially the same shape and size as the inside cross section of said container, and leaves depending from edges of said top wall, said leaves having a width corresponding to the length of said slots and passable through said slots between said side walls and said flaps, said leaves having a height such that a portion of said leaves extends below said downwardly facing flap edges when said top wall rests on the top of said container, and securing structure on said extending leaf portions and engageable beneath said downwardly facing flap edges so as to prevent removal of said cover, said cover being entirely within the confines of a vertical projection of said container.

8. In the combination of claim 7, said side walls having finger holes opposite said securing structure when said cover top wall rests on the top of said container, thereby providing access to said securing structure, said securing structure being normally located in the plane of said leaves but bendable out therefrom into edge-engaging position.
